UNITED STATES PATENT OFFICE

EDWARD G. ROWLEY, OF BELLEVILLE, NEW JERSEY, ASSIGNOR TO UNDERWOOD & ELLIOTT FISHER COMPANY, OF NEW YORK, N. Y., A CORPORATION OF DELAWARE

TYPEWRITING MACHINE

Application filed June 30, 1927. Serial No. 202,620.

This invention relates to platen-adjustment in type-writing machines, and will be shown in particular as being applied to the portable type of the Underwood machine, the object being to simplify and to improve heretofore adjustment-devices and arrangements.

Said adjustment, which is to afford proper relation between the platen and the printing plane, is of great importance, as it governs the clearness and evenness of the imprints, and is necessary since the type-bars are limited in their movement towards the platen by the usual abutment.

It has been customary to effect the adjustment by means of certain links of a parallel link-system, which, provided at either side of the machine, is employed to guide the shift-frame, which supports the platen-carriage, in its up-and-down case-shift-movement.

The adjustment is usually a pivotal one, given to the shift-frame and the platen as a whole, in such a way that with suitable construction, the platen-axis is adjusted substantially at right angles to the entire type-face of the type-bars at the time of printing, while the ordinary oscillatory case-shift-movement of the platen remains practically undisturbed and parallel to the printing-plane.

Means of platen-adjustment heretofore in evidence as screws, controlling one of the stationary axes of the link-system and co-operating with additional parts as slide-plates, subsidiary frames, or the like, adjustably fastened to the main frame, have been rather inaccessible hidden at the rear part of standard machines, complicating their mechanical structure and especially discomforting readjustment of the platen while requiring partial disassembling of the machine.

One feature of the invention is to bring the adjusting device into ready reach of the expert without necessitating any disassembling.

A novel arrangement provides means of adjustment at the swinging end of the guide-links, whereby readiness and accessibility

will be obtained while kinematic conditions remain unchanged.

Another feature of the invention lies in the novel adjustment-device proper, which, being in the nature of an adjustable eccentric, may be used to alter the connecting points of the links for platen adjustment, and which, due to its compactness, lightness, accuracy of adjustment and cheapness, is especially fit for use in "portables".

Other features and advantages will hereinafter appear.

In the accompanying drawings,

Figure 1 is a perspective view, showing the relation between the stationary machine-frame and the shift-frame, and showing the guide-link-connection for case-shifting. Platen and type-bar are indicated in dot-and-dash.

Figure 2 is a sectional side elevation, showing parts mainly engaged in the case-shift-operation with the new platen-adjusting device attached thereto.

Figure 3 is a detail view of Figure 2, showing the platen, the shift-frame and the case-shift-guide-links. In dot-and-dash are indicated the two extreme positions of shift-frame and platen, as allowed for by the novel adjusting device.

Figure 4 is a view largely broken away and similar to Figure 3, showing the novel adjusting device in modification, and also showing extreme positions of adjustment in dot-and-dash.

Figure 5 is a plan view, diagrammatically, to illustrate means to guide the shift-frame against undue lateral movement.

According to Figure 2, a type-bar 1, abutting the usual segment-stop-ring 1^a, is shown in printing position relatively to the platen 2, which is operated in a carriage 3. The carriage, at its lower part, is provided with track-elements 4 and mounted to travel by means of balls 5 upon track-members 6 and 7, secured to the shift-frame, designated as a whole by the reference numeral 8, whereby track-member 7 is shown to be adjustably fastened to the rear of the shift-frame, in order to allow inaccuracies in the raceway to be corrected. A rack 9, provided at the car-

riage, in combination with a pinion 10, escapement-device 11 and spring-drum 12, is to indicate the carriage-actuating mechanism. The shift-frame 8, as more clearly shown in Figure 1, includes side plates 13 having forwardly-extending arms 14 provided with ears 15 for attaching the ribbon-mechanism (not shown in the drawing). A rear plate 16 forms, with the side plates 13, a substantially U-shaped structure.

10 The shift-frame, for case-shift-movement relatively to the main frame 17, is guided by swing-arm connections, which are similar to parallel link-connections, and which include upper guide-arms 18 and lower guide-arms 19 at either side of the machine. To simplify the following description, however, only one side of the machine may be considered with reference to said link-connection.

15 20 The lower arm 19 is rigidly secured at its rear end to a rock-shaft 20, which in turn is pivoted to the main frame 17 by screws 21, while its forward end is fastened to the shift-frame by pivots 22. The upper guide-arm 18 correspondingly is pivoted at its rear end to the main frame, and forwardly-pivoted engaged to the shift-frame by means of the novel adjusting device 23, 25 30 which, it should be noted, is placed upon a part of the shift-frame readily accessible in standard constructions.

35 A shouldered-screw 24 may serve as a pivot for the guide-arms 18 and be threaded eccentrically into a disk 25 mainly constituting the adjusting device, and which in turn is fastened to the arm 14 of the shift-frame-structure, preferably by screws 26 passing through arcuate slots 27 concentrically provided in said disk. When it is 40 desired to adjust the shift-frame, the screws are loosened up and the disk rotated, and, due to the guide-arms 18 being carried eccentrically, a rotation of the disk will tend to move the carriage towards or away from the printing point. The shift-frame is thus 45 given a tilting movement about pivots 22, and the two extreme positions hereby reached are indicated in Figure 3 in dot-and-dash.

50 After the screws 26 are tightened up again, the disk 25 may further be locked in place by suitable devices, such as notches 28 circumferentially provided on the disk, 55 and a pin 29 to fit the notches and which is rigidly secured to the shift-frame. This notch arrangement obviously will also aid in fine adjustment, and the diameter of the disks and the size and pitch of the notches 60 may be formed accordingly to give a measure for the extent of rotation relatively to the shift-frame.

In Figure 4 is shown a modification of the 65 adjusting device. A bracket 30 is movably fastened to the shift-frame by screws 31

passing through straight slots 32 provided in the bracket, so that by loosening up the screws, the frame may be adjusted to bring the carriage towards or away from the printing point. After the adjustment is made, the screws are tightened up again to 70 secure the bracket in place.

To actuate the case-shift mechanism, as described above, for writing upper case-characters, a key-operated lever 33, Figure 2, fulcrumed at 34 in connection with the main frame, is provided with an inwardly-projecting pin 36, secured to the shift-frame and shown to be integral with the pivots 22 (see Figure 1). Upon depression of the lever 33, the extension 35 will cam upwardly pin 36, imparting motion to the shift-frame, which is limited for upper and lower case-positions by stop-screws 37 and link guided, as described above, whereby said stop-screws adjustably threaded into ears 38 struck up from the main frame 17 and locked in place by lock-nuts 39, are to serve as abutments for an extension 40 provided on the right hand lower guide-arm 19. When the operating pressure is released, the shift-frame will gravitate downwardly to rest its weight upon the lower stop-screw 37, while the case-shift-lever 33 swings back to its initial position where it is held, while ineffective, by a spring 41, which causes an ear 42, provided upon the extension 35, to bear against the edge 43 of an opening provided in the side wall of the main frame.

100 A means to guide the shift-frame 8 against undue lateral movement is shown in Figure 5. At the right-hand side, the shift-frame is held by a rigid stop formed with a shouldered screw 44, threaded into the main frame and equally used as a pivot for the right hand upper guide-arm 18, while the left hand side of the shift-frame is taken care of by an adjustable stop, including a tapped and collared hub 45, jointly to be used as a pivot for the left hand upper guide-arm 18 and also a lock-nut cooperative with a lock-nut 46, to provide a stop-screw 47 adjustable relatively to the main frame into which it is threaded, and relatively to the shift-frame, which it is to guide.

105 110 From the foregoing, it will be seen that the new adjusting device in construction and arrangement marks an improvement especially important for portable typewriters, where, due to their lightness and springiness in structure, dislocation of the platen may more easily occur, and where compactness, lightness, cheapness and accuracy in 115 operation combined are vital factors.

120 Variations may be resorted to within the scope of the invention, and portions of the improvements may be used without others.

Having thus described my invention, I claim:

1. In a typewriting machine including a main frame, a carriage mounted for case-shift movement and swinging type-bars, the combination of a system of swingable arms carried by the main frame, said system including a pair of arms, an upper and a lower one, with their swinging ends extending forwardly at either side of the machine, a shift-frame within the main frame supporting the carriage and to be guided by said arms for case-shift movement, and an eccentric device at either side of the case-shift frame including a disk rotatably fastened to the shift-frame and carrying eccentrically one end of one of said upper arms, said disk to be rotated to adjust the shift-frame relatively to the main frame to secure proper relation between said carriage and said type-bars.
2. In a typewriting machine including a main frame, a carriage mounted for case-shift movement and swinging type-bars, the combination of a system of swingable arms carried by the main frame, said system including a pair of arms, an upper one and a lower one, with their swinging ends extending forwardly at either side of the main frame, a shift-frame within the main frame supporting the carriage and to be guided by said arms for case-shift movement, and an eccentric device at either side of the shift-frame, effective to adjust the position of the shift-frame with reference to the main frame for proper relation between the carriage and type-bars, said device including a disk rotatably fastened to the shift-frame and eccentrically carrying one end of said upper arms and having concentric slots to serve as guides for its rotary movement for adjustment upon the shift-frame in co-operation with pins or screws fastened to the shift-frame within the slots.
3. In a typewriting machine including a main frame, a carriage mounted for case-shift movement and swinging type-bars, the combination of a system of swingable arms carried by the main frame, said system including a pair of arms, an upper and a lower one, with their swinging ends extending forwardly at either side of the machine, a shift-frame within the main frame supporting the carriage and to be guided by said arms for case-shift movement, and an eccentric device at either side of said shift-frame to allow the same to be adjusted relatively to the main frame to obtain proper relation between the carriage and the type-bars, said device including a disk rotatably fastened to the shift-frame, an eccentric carrying one end of one of said upper arms, and a locking device to lock said disk in place.
4. In a typewriting machine including a

main frame, a carriage mounted for case-shift movement and swinging type-bars, the combination of a system of swingable arms carried by the main frame, said system including a pair of arms, an upper and a lower one, at either side of the main frame, having their swinging ends extending horizontally forwardly, the upper ones being conveniently accessible to the operator, a shift-frame within the main frame supporting the carriage and to be guided by said arms for case-shift movement, and means adjustably connecting said upper arms to the shift-frame, to allow either side of the shift-frame to be adjusted independently relatively to the main frame, to obtain proper relation between the carriage and the type-bars.

5. In a typewriting machine including a main frame, a carriage mounted for case-shift movement and swinging type-bars, the combination of a system of swingable arms carried by the main frame, said system including a pair of arms, an upper and a lower arm, with their swinging ends extending forwardly at either side of the main frame, a shift-frame within the main frame supporting the carriage and to be guided by said arms for case-shift movement, and an eccentric device at either side of the shift-frame to allow the shift-frame to be adjusted relatively to the main frame to obtain proper relation between the carriage and the type-bars, said device including a disk rotatably connected to the shift-frame and eccentrically carrying one end of one of said upper arms, and a locking device to lock said disk in place including a pin to be fastened to the shift-frame and co-operative with notches which are circumferentially formed on said disk.

6. In a typewriting machine including a main frame, a carriage mounted for case-shift movement and swinging type-bars, the combination of a system of swingable arms carried by the main frame, said system including a pair of arms, an upper and a lower one, with their swinging ends extending forwardly at either side of the machine, a shift-frame within the main frame supporting the carriage and to be guided by said arms for case-shift movement, and an eccentric device at either side for changing the effective lengths of the upper arms, said device including a disk rotatably fastened to the shift-frame and carrying eccentrically one end of one of said upper arms, said disk to be rotated to adjust the shift-frame relatively to the main frame for proper relation between carriage and type-bars.

7. In a typewriting machine including a main frame, a carriage mounted for case-shift movement and swinging type-bars, the combination of a system of swingable

arms carried by the main frame, said system including a pair of arms, an upper one and a lower one, with their swinging ends extending forwardly at either side of the main frame, a shift-frame within the main frame supporting the carriage and to be guided by said arms for case-shift movement, and an eccentric device at either side for changing the effective lengths of the upper arms to allow the shift-frame to be adjusted relatively to the main frame for proper relation between carriage and type-bars, said device including a disk rotatably fastened to the shift-frame and eccentrically carrying one end of one of said upper arms and having concentric slots to serve as guides for its rotary movement for adjustment upon the shift-frame in cooperation with pins or screws fastened to the shift-frame within the slots.

8. In a typewriting machine including a main frame, a carriage mounted for case-shift movement and swinging type-bars, the combination of a system of swingable arms carried by the main frame, said system including a pair of arms, an upper and a lower one, with their swinging ends extending forwardly at either side of the main frame, a shift-frame within the main frame supporting the carriage and to be guided by said arms for case-shift movement, and an eccentric device at either side for changing the effective lengths of the upper arms, to allow the shift-frame to be adjusted relatively to the main frame to obtain proper relation between the carriage and the type-bars, said device including a disk rotatably fastened to the shift-frame and eccentrically carrying one end of one of said upper arms, and a locking device to lock said disk in place.

9. In a typewriting machine including a main frame, a carriage mounted for case-shift movement and swinging type-bars, the combination of a system of swingable arms carried by the main frame, said system including a pair of arms, an upper and a lower arm, with their swinging ends extending forwardly at either side of the main frame, a shift-frame within the main frame supporting the carriage and to be guided by said arms for case-shift movement, and an eccentric device at either side for changing the effective lengths of the upper arms, to allow the shift-frame to be adjusted relatively to the main frame to obtain proper relation between the carriage and the type-bars, said device including a manually-operable disk rotatably connected to the shift-frame and eccentrically carrying one end of one of said upper arms, and a locking device to lock said disk in place including a pin to be fastened to the shift-frame and co-operative with notches which are circumferentially provided on said disk.

10. In a typewriting machine including a main frame, a carriage mounted for case-shift movement and swinging type-bars, the combination of a system of swingable arms carried by the main frame, said system including a pair of arms, an upper and a lower one, with their swinging ends extending forwardly at either side of the main frame, a shift-frame within the main frame supporting the carriage and to be guided by said arms for case-shift movement, and a manually-operable eccentric device at either side for changing the effective lengths of the upper arms, to allow the shift-frame to be adjusted relatively to the main frame to obtain proper relation between the carriage and the type-bars, said device including a disk rotatably fastened to the shift-frame and eccentrically carrying one end of one of said upper arms and having circumferentially-disposed notches or graduations to indicate the amount of rotation of the disk relative to the shift-frame.

11. In a typewriting machine including a main frame, a carriage mounted for case-shift movement and swinging type-bars, the combination of a system of swingable arms carried by the main frame, said system including a pair of arms, an upper and a lower one, with their swinging ends extending forwardly at either side of the main frame, a shift-frame within the main frame supporting the carriage and to be guided by said arms for case-shift movement, and an eccentric device at either side of the shift-frame to allow the shift-frame to be adjusted relatively to the main frame to obtain proper relation between the carriage and the type-bars, said device including a disk rotatably fastened to the shift-frame and eccentrically carrying one end of said upper arms and having circumferentially-disposed notches or graduations to indicate the amount of rotation of the disk relative to the shift-frame.

EDWARD G. ROWLEY.
